(57) **CLAIM**

I claim the ornamental design for a phone case, as shown and described.

DESCRIPTION

FIG. 1 is a top-rear isometric view of a phone case showing my design;

FIG. 2 is a bottom-front isometric view thereof;

FIG. 3 is a front plan view thereof;

FIG. 4 is a rear plan view thereof;

FIG. 5 is a right side view thereof;

FIG. 6 is a left side view thereof;

FIG. 7 is a bottom plan view thereof;

FIG. 8 is a top plan view thereof;

FIG. 9 is a top-rear isometric view of an alternative embodiment of the phone case showing my design;

FIG. 10 is a bottom-front isometric view thereof;

FIG. 11 is a front plan view thereof;

FIG. 12 is a rear plan view thereof;

FIG. 13 is a right side view thereof;

FIG. 14 is a left side view thereof;

FIG. 15 is a bottom plan view thereof; and,

FIG. 16 is a top plan view thereof.

The evenly broken lines in the drawings depict unclaimed portion of the phone case, and the dash-dot broken lines disclose unclaimed environmental subject matter; the broken lines form no part of the claimed design.
